UNITED STATES PATENT OFFICE.

MICHAEL STOPPER, OF CINCINNATI, OHIO.

DESIGN FOR A BREASTPIN.

SPECIFICATION forming part of Design No. 25,825, dated July 21, 1896.

Application filed May 18, 1896. Serial No. 592,061. Term of patent 31 years.

To all whom it may concern:

Be it known that I, MICHAEL STOPPER, a citizen of the United States, residing at Cincinnati, in the county of Hamilton, State of Ohio, have invented a new and useful Improvement in Designs for a Breastpin, of which the following is a full, clear, and exact description, reference being had to the accompanying drawings, forming part of this specification.

In the drawings, Figure 1 is a front view of my breastpin somewhat enlarged. Fig. 2 is a side view of same.

The design represents a peacock standing on a grassy plot of ground with his tail spread

out behind him. The representation of the tail of the peacock is mounted on a disk or plate at the back of the bird, and surrounding the tail-disk are a series of concentric rings studded with gems.

Having thus described my design, what I claim, and desire to secure by Letters Patent, is—

The design for a breastpin, substantially as shown and described.

MICHAEL STOPPER.
